UNITED STATES PATENT OFFICE.

FRANK B. SANBORN, OF CAMBRIDGE, MASSACHUSETTS.

PULSE-WAVE RECORDER.

Application filed June 13, 1923. Serial No. 645,173.

To all whom it may concern:

Be it known that I, FRANK B. SANBORN, a citizen of the United States, residing at Cambridge, in the county of Middlesex and 5 State of Massachusetts, have invented a new and useful Pulse-Wave Recorder, of which the following is a specification.

This invention concerns apparatus for producing a record of the expansion and 10 contraction of blood-vessels, as the veins and arteries, for clinical purposes. In this connection, very small actuating forces are dealt with, and they must overcome substantial resistances in the inertia of the transmitting and recording elements. Objects 15 of the invention are to effectively receive the impulses from the blood-vessels, and to generally render the recording apparatus convenient and reliable in use.

20 In the accompanying drawing, Fig. 1 illustrates, in perspective, one embodiment of my invention; Fig. 2 is an enlarged longitudinal, vertical, sectional detail through the impulse-receiving chambers; Fig. 3 is a 25 front elevation of one of said chambers, with parts broken away; and Fig. 4 is a perspective view of such chamber.

Similar characters of reference are applied to like parts throughout the several 30 views of the drawing.

Near one extremity of a base-plate 10 is fixed a standard 12 having, projecting at opposite sides of its upper end, brackets 14, 14 to support impulse-receiving chambers 16, 35 16. These chambers act in exactly the same manner to respectively produce simultaneous tracings from different blood-vessels, as a vein and an artery, and are organized in substantially the same manner. Conse- 40 quently, but one will be described in detail. Considering, then, one section of this double receiving mechanism, its bracket 14 is slotted longitudinally at 17 to receive a nipple 18, which is a part of an inlet-conduit com- 45 municating with the chamber and continued from said chamber by a flexible pipe 20. At the outer extremity of this pipe is connected any convenient form of transmitting device (not illustrated), as a chamber closed at one 50 side by an elastic diaphragm, which, when applied to the blood-vessel from which a record is to be produced, transmits to the receiving mechanism impulses in the air contained in the system, and set up by the ex-

pansions and contractions. The nipple 18 55 enters an inlet-opening of the chamber 16, this opening being formed in a plate 22 furnishing the outer wall of the chamber. The plate is clamped against the inner face of the bracket 14 by a nut 24 threaded upon 60 the nipple and contacting with the opposite or outer side of the bracket to hold the chamber in place. The front wall of this receiving chamber consists of a diaphragm 65 26, of some such elastic material as sheet rubber, secured to the periphery of the plate by a band 28. Surrounding the inlet-opening, preferably concentric with the circular periphery of the plate 22, is a wall 30 projecting from the inner face of the plate toward the diaphragm, which, as it is drawn about the plate by the securing band, contacts firmly with said wall. The height or outward extension of this wall, which is much less than the distance between its opposite sides, is such as to furnish a relatively shallow space beneath the diaphragm, this space constituting the receiving chamber. The cubic capacity of the space is small as compared with the air displaced at the 70 transmitting device by the pulsation of the blood-vessel. Consequently, there are produced movements of the diaphragm of substantial extent. The shallowness of the 75 chamber and resultant proximity of the dia- phragm to the inlet-opening through the plate 22 give effective impact of the air-im- pulses without dissipation of their energy. Moreover, the plate furnishes a stop-surface 80 with which the diaphragm promptly contacts if suction is applied to the pipe 20, so that rupture of the diaphragm is prevented. Be- 85 tween the wall 30 and the periphery of the plate there is formed, beneath the dia- phragm, an auxiliary chamber 32, normally 90 separated from the main chamber 16. From this auxiliary chamber, through the plate 22, is a contracted opening 34. If undue pres- 95 sure be applied to the pipe 20, the dia- phragm, expanding, will leave the outer ex- tremity of the wall 30, causing the air in the transmitting and receiving system to flow over the top of the wall into the chamber 32 and through the opening 34, thus relieving 100 the diaphragm from dangerous stresses. This outer chamber and its opening are also effective in lessening strains upon the dia- phragm in the opposite direction, as under

the influence of suction. In this case, the contact between the wall 30 and the diaphragm becomes imperfect, so that air is permitted to pass through the opening 34, 5 the chamber 32 and between the diaphragm and wall, and balance atmospheric pressure against the outer face of the former. While the normally effective diaphragm-area is confined within the wall 30, the total area 10 from the periphery of the plate 22 gives greater elasticity than would one of less extent and a higher degree of responsiveness to applied impulses, there being capacity to yield from the peripheral securing means. 15 On the other hand, the normal flexing being only of that portion within the wall, the inertia of the part moved is minimized. Then, too, because of the relief or compensating effect between the main and auxiliary 20 chambers, a thinner, lighter and more elastic diaphragm may be used without danger of rupturing. This increases the sensitivity of the apparatus.

Fixed to the center of the diaphragm, as 25 by an adhesive, is a thin plate 36 having a contact-projection 38. Resting against the outer extremity of this projection or stud, which is flattened horizontally to be of some lateral extent substantially parallel to the diaphragm, is a vertical contact member 40, of 30 generally inverted U-form, fixed to the arm of a recording lever 42. Since it is desired that the levers of both receiving chambers shall be maintained against their studs by a 35 force acting in the same direction, this being gravity, the engagement between the contact members and studs is at the opposite sides of the fulcra of the levers. That is, the lever seen at the right of Fig. 1 has its contact member 40 fixed to its long arm, while 40 upon the associated lever, the contact member is secured to a short arm at the opposite side of the fulcrum, this being as appears in Figs. 3 and 4. Referring particularly to Fig. 4, it will be noted that the ends 45 of the studs or projections 38 and the members 40, which are in contact, are of relatively small transverse dimensions, and are extended longitudinally, crossing each other 50 at an angle, so that they give proper engagement during movement of the elements, and yet engage over so small an area as to minimize friction. These intersecting edges, of considerable longitudinal extent, also facilitate the assembling of the apparatus, lessening the precision of workmanship required. The fulcrum of each of the recording levers 42 may be furnished by opposed 55 conical pointed screws 44, 44' threaded through an arm 46 projecting from the bracket 14. Because of the relatively great extent of movement of the diaphragm upon the chamber 16 of small cubic capacity, and under considerable force of the direct impact of impulses from the inlet-opening of

the nipple 18 in close proximity to the diaphragm, the ratio of the short arm of the lever, between the point of contact of the member 40 and the fulcrum, and the long arm of said lever, which, at its outer extremity, carries a recording device, need not be very great, the increase in the length of the short arm providing greater power to overcome inertia and resistance. Hinged at 48, 70 upon the long arm of the lever 42, is a recording pen 50, which may be trough-shaped to contain a considerable supply of ink. To hold the members 38 and 40 in operating contact, so that the pen may be caused to follow the fluctuations of the diaphragm, 75 under the influence of the impressed impulses from the expanding and contracting blood-vessel, the force of gravity is utilized. This force is made effective by inclining the base 10 upon one edge 52 by means of a 80 skeleton-leg 54, pivoted at 56 beneath the base. The pivoting of the leg allows it to be brought into parallelism with the base, so that the apparatus may be more conveniently packed for transportation. When thus 85 inclined, the weight of the long arm of the lever forces this down against the contact member 40 of one chamber, and moves the short arm 55 up against said member of the other chamber, their engagement in each 90 case being constantly maintained. Such a connecting means, with capability for independent movement between the elements, is highly advantageous as compared with such a positive articulation as would be furnished 95 by a link, since friction is to a great degree eliminated, and there is no tendency for the engaging parts to bind and resist movement through errors in assembling or through distortion in use. Secured to the 100 bracket 14 and extending on opposite sides of the lever 42 is an arm 57, which serves as a stop to guard the elements against excessive oscillation of the lever in either direction. 105

Adjacent to the edge 52 of the base is attached a casing 58, containing a clockwork or other motor mechanism to advance, in constant time relation, the surface upon which the pens are to record the received 110 impulses. This surface is preferably furnished by a ribbon of paper 60, which is taken from a supply-roll 62 mounted upon a spindle 62' projecting from the inner wall of the casing and is received by a winding 115 roll 64, the spindle 65 of which is turned by the motor mechanism within the casing. The rolls are so mounted as to be readily separable, to permit the application and removal of the ribbon. If desired, supports may be 120 furnished for the outer ends of the spindles, a bracket 66 being illustrated for that purpose in connection with the spindle 65 of the winding roll. Guides 68 and 70 are situated 125 respectively below and above the ribbon, 130

projecting horizontally from the inner side of the casing. The former serves as a table, over which the pens act. The latter maintains the ribbon smoothly in contact with 5 this table.

With the transmitting devices in place over an artery and a vein of a person to be examined, the expansion and contraction of these cause impulses of alternately compressed and expanding air to act through the pipes 20, expanding and contracting the diaphragms 26. This moves each of the studs 38 back and forth, acting through the contact members 40 upon levers 42 to carry 10 the pens 50 transversely of the ribbon 60. Since the surface of this ribbon is advancing at a regular rate beneath the pens, there are inscribed upon it lines in wave form, which record the action of the blood-vessels under 15 observation. At 72, a tracing made from an artery appears, and at 74 one from a vein. To furnish convenient means for determining the timing of the received wave, an additional pen 76 may act near the inner edge 20 of the ribbon, this being actuated by clock-work to produce marks 78. These marks preferably indicate seconds, every fifth indication being omitted to make the time more readily readable. A knob 80, projecting 25 through a slot in the casing, serves, by its movement, to start and stop the motor mechanism for the ribbon, while a similar knob 82 gives control over the clockwork actuating the pen 76. A hook 84 is fixed to 30 the upper surface of the base at the edge opposite the casing 58, this facilitating the handling of the apparatus.

I claim:

1. A pulse-wave-recording apparatus comprising an impulse-receiving chamber having an inlet-opening, a contact-wall surrounding the opening, a diaphragm stretched across the wall to form one side of the chamber, means spaced from the wall 40 for securing the diaphragm in place, and recording mechanism under the influence of the diaphragm.

2. A pulse-wave-recording apparatus comprising an impulse-receiving chamber having an inlet-opening, a contact-wall surrounding the opening, a diaphragm stretched across the wall to form one side of the chamber, means spaced from the wall 50 for securing the diaphragm in place, there being an auxiliary chamber between the wall and securing means, and recording mechanism under the influence of the diaphragm.

3. A pulse-wave-recording apparatus comprising an impulse-receiving chamber having an inlet-opening, a contact-wall surrounding the opening, a diaphragm stretched across the wall to form one side of the chamber, means spaced from the wall 60 for securing the diaphragm in place, there being an auxiliary chamber between the wall 65

and securing means from which auxiliary chamber is an opening, and recording mechanism under the influence of the diaphragm.

4. A pulse-wave-recording apparatus comprising an impulse-receiving chamber having an inlet-opening, a contact-wall surrounding the opening, a diaphragm stretched across the wall to form one side of the chamber, the diaphragm being in close proximity to the inlet-opening, means 70 for holding the diaphragm stretched across the wall, and recording mechanism actuated by the diaphragm.

5. A pulse-wave-recording apparatus comprising a plate through which is an opening, 80 an inlet-tube connected to the opening, a wall surrounding the opening between it and the periphery of the plate, a diaphragm contacting with the outer extremity of the wall and with the periphery of the plate, 85 and recording mechanism actuated by the diaphragm.

6. A pulse-wave-recording apparatus comprising a plate through which is an opening, 90 an inlet-tube connected to the opening, a wall surrounding the opening between it and the periphery of the plate, there being an opening through the plate between its periphery and the wall, a diaphragm contacting with the outer extremity of the wall and with the periphery of the plate, 95 and recording mechanism actuated by the diaphragm.

7. A pulse-wave-recording apparatus comprising a plate through which is an opening, 100 an inlet-tube connected to the opening, a wall surrounding the opening between it and the periphery of the plate, the height of said wall being much less than the distance between its opposite sides, a diaphragm stretched across the outer extremity 105 of the wall, and recording mechanism under the influence of the diaphragm.

8. A pulse-wave-recording apparatus comprising an impulse-receiving diaphragm, and a recording member arranged to be held 110 by gravity in co-operation with the diaphragm.

9. A pulse-wave-recording apparatus comprising an impulse-receiving diaphragm, a member carried thereby, and a recording lever having a portion normally resting against the member but free to move independently thereof.

10. A pulse-wave-recording apparatus comprising an impulse-receiving diaphragm, 120 a member carried thereby, and a recording lever having a portion normally resting against the member but free to move independently thereof, the contacting portions being narrow and crossing each other at an 125 angle.

11. A pulse-wave-recording apparatus comprising a chamber having a movable wall, a projection from the wall having a terminal portion extending substantially 130

parallel to said wall, and a recording lever normally maintained by gravity in contact with such terminal portion of the projection.

12. A pulse - wave - recording apparatus comprising a plate through which is an opening, an inlet-tube connected to the opening, a flange surrounding the opening between it and the periphery of the plate, a diaphragm stretched across the flange, means for securing the diaphragm to the periphery of the plate, a stud projecting from the diaphragm between opposite portions of the flange, and a recording lever bearing against the extremity of the stud.
13. A pulse - wave - recording apparatus comprising a base, means for holding the base in an inclined position, and recording mechanism including elements maintained in operative relation by virtue of the inclination of the base.
14. A pulse - wave - recording apparatus comprising a base, means for holding the base in an inclined position, an impulse-

receiving chamber having a movable projection, and a recording lever maintained in contact with the projection by the inclination of the base.

15. A pulse - wave - recording apparatus comprising a base, impulse-receiving mechanism carried by the base, recording mechanism mounted near one edge of the base, and a supporting leg pivoted near the opposite side of the base from the recording mechanism.

16. A pulse - wave - recording apparatus comprising a base, impulse-receiving mechanism mounted thereon, a pen actuated by said mechanism, supports for a record-ribbon, a casing carried by the base and containing motor mechanism for the ribbon, and a guide for the ribbon extending from the side of the casing adjacent to the pen.

Signed at Boston, in the county of Suffolk and State of Massachusetts, this fourth day of June, 1923.

FRANK B. SANBORN.
